UNITED STATES PATENT OFFICE.

NEWMAN H. HOLLAND, OF BROOKLINE, MASSACHUSETTS, ASSIGNOR OF
ONE-HALF TO CHARLES BATE, OF QUINCY, MASSACHUSETTS.

TELEPHONE-METER.

No. 838,115.

Specification of Letters Patent.

Patented Dec. 11, 1906.

Application filed January 31, 1902. Serial No. 92,053.

To all whom it may concern:

Be it known that I, NEWMAN H. HOLLAND, of Brookline, county of Norfolk, and State of Massachusetts, have invented an Improvement in Telephone-Meters, of which the following description, in connection with the accompanying drawings, is a specification, like letters on the drawings representing like parts.

10 The present invention relates to a telephone-meter, and is embodied in a local instrument adapted to be located at the subscriber's station, the object of the invention being to obtain an instrument which can be 15 installed without altering or disturbing any of the circuits or apparatus at the central office.

20 A further object of the invention is to provide means whereby the subscriber calling 25 for a connection can communicate with central office and be assured that the line he desires has been connected before his meter has been operated, the operation of the meter, however, being necessary before conversation 25 can be carried on with the other party.

30 A further object of the invention is to arrange the instrument so that the called-subscriber's instrument will be in condition 35 for communication without any operation of the meter, it being the purpose to register the calls only at the station where the calls originate. To accomplish this purpose, the transmitter-circuit, upon the completion of which the ability of the subscriber to communicate with another subscriber depends, is provided with a circuit-controller through 40 which the circuit is open after a subscriber has sent in a call, the instrument being provided with means under the control of the 45 subscriber for closing the said circuit, the said means, however, being so arranged that they cannot be operated without making a record. The circuit, however, is provided with a secondary circuit-controller which is 50 only partially under the control of the subscriber, the said subscriber being able to use this device to close the circuit temporarily, the said circuit, however, being automatically broken at the end of a predetermined 55 interval of time. This interval of time is sufficient to enable the subscriber to communicate his wishes to the central office and to ascertain if the line he desires to be con-

nected with is available and connected. This interval of time can be sufficiently long 55 to practically assure that the subscriber will obtain the connection without, however, being long enough to enable him to carry on any conversation with the other subscriber. The transmitter-circuit being broken automatically at the end of such interval of time, it is necessary to operate the other circuit-controller, and consequently the meter, the operation of the other circuit-controller being such that the circuit will remain closed as 60 long as the instrument is in use. This circuit-controller, however, is arranged to cause the circuit to be broken in response to an outgoing signaling impulse, so that the act of signaling central opens the circuit, which 65 cannot again be closed without operating the meter. The receiver-circuit, however, is always closed, so that the subscriber can hear the operator at central, so that the timed circuit-controller need not be operated 70 until after the operator has answered. The instrument is provided, however, with means whereby the circuit will be closed at a station receiving a call, so that the subscriber at such station can carry on conversation 75 without operating his meter.

The invention is applicable to either the local-battery or central-energy systems, and to illustrate the invention it is herein shown as applied to each of the said systems, the 80 construction shown being in each case a practical embodiment of the invention, it being obvious, however, that modifications can be made without departing from the invention.

Figure 1 is a diagram of circuits at a subscriber's station, illustrating the meter embodying the invention as applied to the local-battery system; and Fig. 2 is a similar diagram illustrating the invention as applied to a central-energy system.

The meter a , which may be a recording instrument of any suitable type, being conventionally shown as a train of wheels, is adapted to be operated manually, as by a push-button a^2 , under the control of the subscriber, the arrangement being such that the operation of this push-button is essential to the completion of the transmitter-circuit for carrying on conversation after originating a call. By the foregoing statement it must be understood that this is the condition only at

the station which has originated the call, the instrument at the station receiving the call being in condition for conversation without any operation on the part of the subscriber. In the local-battery system illustrated in Fig. 1 the transmitter-circuit is arranged to be broken in response to an impulse of current from the generator G, which is utilized in sending a call to central office.

Without for the present tracing the transmitter-circuit, it may be stated that the break above mentioned is caused by a circuit-controller b, which is shown as operated by the armature b², which is under the influence of two electromagnets c and c², the electromagnet c², which causes the breaking of the circuit, being energized by the outgoing signaling-current. The circuit of the outgoing signaling-current may be traced from the generator G through the conductor G¹, push-button G², conductor G³, through the electromagnet c², conductor G⁴, conductor G⁵, the bells d, conductor G⁶, back to the magneto G. This circuit is in shunt with the line-circuit over which the current travels to central office to operate the drop, the current dividing at the push-button G² and passing through the conductor G², gravity-hook H, conductor G¹, to one side of the line and back over the other side of the line to conductor G², which connects at G² with the conductor G⁵. The operation of the magneto to call central therefore energizes electromagnet c², attracting the armature b² toward said electromagnet and moving the contact member b to break the circuit, as shown in the drawings. As this break occurs only in the transmitter-circuit, the subscriber upon taking down the receiver can hear the operator at central office, if she answers, and upon getting an answer in order that the subscriber may communicate his wishes to the operator at central office without operating his meter the instrument is provided with means independent of the meter for temporarily closing the transmitter-circuit, there being a timing device of some suitable kind to maintain such closure a sufficient length of time to permit the necessary communication with central office, at the end of which time the circuit opens automatically, leaving the subscriber unable to carry on conversation without making a further closure of the circuit, which necessitates the operation of the meter a. As herein shown, the temporary circuit-closer is arranged to be operated by means of a push-button e, having a restoring-spring e², the said push-button acting upon a contact member e³, which is shown as arranged to make contact with the member e⁴ and to be retarded in its return movement, as by a dash-piston e⁵, the said contact member e³ for convenience being shown as the body of a dash-pot, it being obvious, however, that

any suitable retarding device which will permit a gradual restoration of said member to normal may be employed.

In order to prevent the subscriber from maintaining the circuit closed by keeping the push-button e pressed in, the said push-button also controls a secondary circuit-closer comprising the members e¹⁰ and e¹¹, which are normally held together by means of an insulated shoulder e¹², carried by the push-button e, but which are adapted to spring apart as soon as the push-button is pressed in to operate the member e¹³. It is necessary, therefore, in order to obtain the temporary closure of the circuit, that the subscriber should first push the button e and then permit the same to return to its normal position. The circuit thus closed may be traced as follows, starting from the local battery B: From the said battery current passes over conductor B¹ to conductor B², conductor B³, thence through the circuit-controller members e¹ and e² to a conductor B⁴, thence through the circuit-controlling members e¹⁰ and e¹¹ to the conductor B⁵, thence through conductor B⁶, conductor B⁷, conductor G² to the gravity-hook H, conductor B⁸, transmitter T, coil S, conductor B⁹, to the other side of the local battery B. The timing device or dash-pot is so timed as to give the subscriber abundant opportunity to repeat the number desired, if necessary, and to be assured that his connection has been accomplished in order that he may not be called upon to operate his meter unnecessarily.

To prevent the subscriber from carrying on conversation by repeatedly operating the push-button e, the said button is normally locked and arranged to be temporarily released in response to an outgoing signaling-current. As herein shown, the member e³ is provided with a locking-shoulder e¹⁴, in the path of which is a detent e¹⁵. The said detent e¹⁵ is influenced by current flowing through the coils of an electromagnet e¹⁶ in the outgoing signaling-circuit. When a signal is sent out, therefore, the detent e¹⁵ is moved out of the way and held by a locking device e¹⁷, shown as a spring-catch. This locking device, however, is arranged to be operated upon by the member e³, which engages the spring-catch and releases the detent, which then stands in position to lock the member e³. It will be seen, therefore, that the subscriber cannot carry on conversation by means of the push-button e without repeatedly sending out signals. In order to continue the conversation, however, after the circuit thus traced has become broken, it is necessary only to close the circuit by means of the circuit-controller b, this being accomplished by pushing the button a². As herein shown, the said push-button a² is connected with a rod which is adapted to

operate upon an extension of the armature b^2 , so as to force the contact member b into contact with an operating contact member b^3 , and the armature b^2 is so arranged as to stay in whatever position it has been caused to assume under the influence of current passing through the electromagnets c or c^2 . The same movement of the push-button a^2 , as indicated, operates the meter a , thus recording the use of the instrument. The transmitter-circuit is then completed through the conductor B' , the contact member b^3 , the contact member b , the conductor B^{10} , conductor G^{21} , gravity-hook H , &c., as before.

In case the subscriber is called his instrument will be in condition for use without operating the meter, since the circuit-controller b , if not already in position to close the transmitter-circuit, will be moved to such position under the influence of the incoming signaling-current, which energizes the electromagnet c , which is included in the incoming signaling-circuit.

Without tracing the entire incoming signaling-circuit, it is sufficient to state that a shunt or branch of said circuit starts at C , passing through the conductor C^2 , electromagnet c , to the conductor G^4 , which connects with the main portion of the incoming signaling-circuit at G^{23} .

From the foregoing description it will be seen that the instrument will always be in condition for use after a signal has been received, but that it cannot be used after a signal has been sent without first operating the recording mechanism. At the same time the subscriber is amply protected against recording unsuccessful calls, as the timing mechanism permits sufficient communication with the central office to ascertain whether or not a successful connection has been made.

In the central-energy or common-battery system the method of operation is substantially the same, and but slight modifications of the circuits are required, the main difference being that the transmitter-circuit is arranged to be opened at b in response to the movement of the gravity-hook when the receiver is hung up, the incoming signaling-current causing the circuit to be closed at b , as before.

It is not deemed necessary to trace the circuits shown in Fig. 2, which are substantially the same as those shown in Fig. 1, with such changes as are necessary to adapt the instrument to the central-energy system, which is too well known to require description. The electromagnet c^2 , however, which causes the breaking of the circuit at b , is arranged to be energized by current flowing over a circuit which is momentarily closed when the receiver is restored to the gravity-hook. For this purpose the gravity-hook H is arranged to make a passing contact with a contact-piece H^2 , momentarily completing the circuit through

conductor G^3 , through the electromagnet c^2 , conductor G^4 , switch member H^2 , gravity-hook H , resistance R , conductor G^{22} , to the other side of the line, thus energizing the electromagnet c^2 and causing the circuit to be broken at b . The circuit remains broken at b until closed either by an incoming call, which is not to be recorded, or by the operation of the push-button a^2 , as in the arrangement already described, which also operates the recording mechanism. The construction and arrangement of the push-button a and the circuit-controllers operated thereby and the secondary circuits at the instrument are substantially the same as those described in detail in connection with those in Fig. 1, and it is not deemed necessary to describe them further in connection with Fig. 2.

It is to be understood that while the construction and arrangement herein shown and described to illustrate the invention constitute a practical embodiment of the invention such construction and arrangement have been chosen mainly for clearness in illustrating the invention and that both the mechanical devices and the arrangement of the circuits may be varied or modified without departing from the invention.

I claim—

1. In a telephone-meter system, a recording instrument at each station; a device located at said station for signaling a central office; a circuit-controller for the transmitter-circuit at each station; means operated by the signaling device, when central office is signaled, for actuating said controller, to prevent the use of the transmitter; and common means, independent of the means operated by said signaling device, for operating said recording instrument and said circuit-controller.

2. In a telephone-meter system, a recording instrument at each station; means located at each station for signaling a central office; a circuit-controller for the transmitter-circuit at each station; means for causing said circuit-controller to open the said transmitter-circuit in response to the operation of the signaling means at the station when a signal is sent to central office; and common means for closing said transmitter-circuit and operating said recording instrument.

3. In a telephone-meter system, a central office; a signaling device at said central office; a local station; means at said local station for operating said signaling device at central office; a circuit-controller for the transmitter-circuit at the local station operated to break said transmitter-circuit in response to the operation of the signaling device to send a signal to the central office; a recording instrument at the local station; and common means for operating said recording instrument and restoring said circuit-controller to close the transmitter-circuit.

4. In a telephone-meter system, a circuit-controller at each station; means for operating said circuit-controller by impulses of current used for signaling; independent means for manually operating said circuit-controller; a recording instrument operated by said independent means; a second circuit-controller; means under control of the subscriber for operating said second circuit-controller; and a 10 timed automatic restoring device therefor, as set forth.

5. In a telephone-meter system, a recording instrument and a circuit-controller provided with common operating means; a 15 second circuit-controller; an operating device therefor; means for locking said operating device; means operating in response to outgoing signaling-currents for unlocking said operating device; and means for automatically restoring said second circuit-controller to normal.

6. In a telephone-meter system, a transmitter-circuit and a receiver-circuit at each station; a signal-receiving and a signal-sending device at each station; a circuit-controller for the transmitter-circuit; a device for operating said circuit-controller to close the transmitter-circuit in response to the operation of the signal-receiving device and for breaking said transmitter-circuit in response 30 to the operation of the signal-sending device; a recording instrument; and a device for closing said transmitter-circuit to permit conversation, and at the same time to operate said recording instrument.

In testimony whereof I have signed my name to this specification in the presence of two subscribing witnesses.
